UNITED STATES PATENT OFFICE.

GRANT SMITH, OF TORONTO, ONTARIO, CANADA.

STOVE.

1,200,252.

Specification of Letters Patent.

Patented Oct. 3, 1916.

Application filed June 15, 1911. Serial No. 633,285.

To all whom it may concern:

Be it known that I, GRANT SMITH, a subject of the King of Great Britain, resident of the city of Toronto, county of York, 5 Province of Ontario, in the Dominion of Canada, have invented certain new and useful Improvements in Stoves; and I do hereby declare that the following is a full, clear, and exact description of the same.

10 The invention relates to improvements in stoves, as described in the following specification and illustrated in the accompanying drawings that form part of the same.

15 The invention consists essentially in the novel construction and arrangement of parts, whereby the gases of combustion are conducted from the fire pot through an annular chamber inclosing a central heating chamber.

20 The objects of the invention are, to obtain the maximum heat radiating surface, to economize in the use of fuel, and to devise a stove which may be utilized wholly for heating purposes, or converted to a combination heating and cooking stove.

In the drawings, Figure 1 is a front elevational view of a stove constructed in accordance with this invention shown partly in vertical section. Fig. 2 is a vertical section 30 perspective detail through the rear of the stove. Fig. 3 is a horizontal sectional view through the line *a*—*b* Fig. 1. Fig. 4 is a sectional perspective detail of a portion of the stove casing and grate. Fig. 5 is an enlarged plan view of the center cone grate. Fig. 6 is a perspective detail of a portion of the draft control damper and support and a portion of the grate.

Like numerals of reference indicate corresponding parts in each figure.

Referring to the drawings, 1 is the base portion of the stove supported on suitable legs 2.

3 is an annular ring formed integral with 45 the inner ends of the radially arranged ribs 4 projecting inwardly from the ring 15 resting on the base 1.

5 is the fire pot preferably formed in the shape of a frustum of a cone and having a lateral flange 6 adjacent to the bottom resting upon the ring 3.

50 The fire pot 5 is formed with a plurality of protuberances 7 on its exterior, said protuberances having upwardly and outwardly

sloping orifices 8 forming exit openings for 55 the gases of combustion.

9 is an annular shaped grid rigidly supported from the base 1 below the fire pot 5, the outer circumference of said grid being about the same diameter or slightly larger 60 than the diameter of the bottom of the fire pot.

10 is a grate ring rotatably supported upon the grid 9 and having the radial bars 11 preferably arched and hollow on the underside. The bars of the ring 10 correspond in number to the bars of the grid 9 and are adapted on the rotation of the ring to close the openings between the grid bars.

12 is a cone shaped grate supported upon 70 the upwardly extending flange 13 of the grid 9 and extending upwardly into the fire box.

14 is a damper ring rotatably supported upon the ribs 4 between the inwardly extending ring portion 15 resting on the base 75 and the rigid ring 3, said damper having a plurality of openings therethrough corresponding in number and size to the ribs 4 so that the said ribs will close the openings.

A casing comprising the shells 16 and 24 80 extends upwardly from the base to the top portion of the stove. The shell 16 incloses an annular chamber 17 around the fire pot 5 and is provided with suitable doors 18.

19 is a ring supported upon the shell 16 85 and the top of the fire pot 5 and having an inwardly extending drop flange 20 projecting inwardly from the inner edge of the fire pot.

21 and 22 are annular flanges on the ring 90 19 extending upwardly substantially in line with the shell 16 and fire pot 5 respectively. The ring 19 is provided with a plurality of orifices 23 arranged between the said vertical flanges 21 and 22. The shell 24 which is 95 preferably of sheet metal is held in place by the flange 21 of the ring 19.

25 is an annular shell resting on the ring 19 and spaced from the shell 24 being held in place by the flange 22, said shells inclosing 100 an annular chamber forming an extension of the chamber 17, the inner shell forming a central heat chamber.

26 is an annular ring resting upon the upper ends of the shells 24 and 25 and having 105 a plurality of orifices 27 therethrough communicating with the chamber 28 between said shells. The inner and outer walls 29

and 30 of the ring 26 extend upwardly from the shells and form an annular chamber 31 communicating with the chamber 28.

32 is a baffle plate encircling the inner wall 29 of the ring 26 and extending part way across the chamber 31 for the major portion of the circumference of said chamber, said plate at the back portion of the stove extending completely between the walls 29 and 30 as shown particularly in Figs. 2 and 3.

33 is a ring resting on the upper edges of the walls of the ring 26 and of inverted dished shape in cross section and completing the chamber 31.

15 34 is the smoke pipe ferrule formed integral with the ring 33 and arranged centrally above the extension portion of the baffle 32. The several sections herein described as forming the body of the stove are suitably cemented and secured together to form gas tight joints to prevent the escape of coal gas when the stove is in use.

35 is an annular plate resting on the depending flange 20 and having a depending flange 36 formed on its inner edge.

37 is a ring preferably formed in the shape of an inverted frustum of a cone having a lateral flange 38 at the upper edge resting upon an inwardly extending flange 39 from the ring 33 and having an inwardly extending flange 40 at the bottom edge.

41 are a plurality of slotted openings in the ring 37.

42 is a ring damper fitting the inner face of the ring 37 and rotatably supported thereon.

43 is a metal cylinder having an outwardly extending flange 44 at the upper end adapted to rest on the depending flange 40 of the ring 37 and a flange 45 at the bottom resting in the depending flange 36 of the plate 35.

46 is an annular recess formed at the upper end of the cylinder 43.

47 is a circular plate resting in the recess 46 and inclosing the top of said cylinder.

48 is a perforated crown piece resting on the top of the ring 33 and covering the top of the stove.

50 49 is a door hinged to the outer shell 24 and closing a door opening through the inner and outer shells leading to the chamber 50 within the inner shell.

55 51 is an arched opening formed by an arch projecting up from the ring 19 preferably at the back of the stove and forming an air passage into the chamber 50 at the bottom thereof. The flanges 21 and 22 extend over this arch to engage the shells 24 and 25.

60 In using this stove the top 48 is removed and the central cylinder 43 is lifted upwardly by means of a suitable handle or grip a sufficient distance to allow the placing of the fuel within the fire pot, the door 49 being opened. When sufficient fuel for

properly lighting the fire has been arranged the cylinder 43 is returned and the top again placed in position and the fire is then lighted. The air entering the base of the stove through suitable dampers passes 70 through the bars of the cone shaped grate 12 and through the fire, the gases of combustion passing outwardly through the ori-fices 8 in the fire pot. The hot gases entering the chamber immediately surrounding 75 the fire pot pass upwardly through the perforated ring 19 and chamber 28 and are deflected outwardly by the baffle plate 32. The baffle plate 32 being arranged to extend completely across the chamber 31 at 80 the back of the stove and immediately beneath the smoke pipe opening prevents the said gases from taking a short cut to the flue, thereby effecting an even distribution and a more effective heating of the radiating surfaces and thereby giving the greatest possible heating efficiency.

When the stove is used exclusively as a heater, the arched opening 51 at the back of the stove is left open and the air is drawn through said opening and circulated through the chamber 50 passing upwardly through the perforated ring at the top of said chamber and out through the perforated crown. A very large heating area is 95 thus exposed to the air in circulation as the gases of combustion are circulated through an annular flue the full diameter of the stove in contact with the air at both sides.

When the cylinder 43 is in place the 100 stove may be used as a self feeder and a supply of coal contained within said cylinder, such supply not interfering in any way with the circulation of air in the chamber 50.

105 In using the stove for cooking purposes the cylinder 43 is lifted out through the top and the plate 47 is then placed in position to close the opening immediately over the fire and a suitable plate may be placed 110 in the ring 37 to close in the oven space thus formed. A suitable closure 52 may be placed to close the arched opening 51. The chamber 50 is thus very quickly converted into a spacious oven having the fire immediately beneath it and the hot gases circulating completely therearound except of course at the door opening in the front of the stove. When the stove is used in this manner the ring damper 42 will be closed. 115 The ring grate 10 fits very closely under the bottom end of the fire pot so that very little air will pass through the fire from the joint and this grate is arranged to close the openings in the grid 9 for the major portion of the time, it being in practice only used as a shaker. The bars of the said ring are preferably arched as described to present as large a surface to the air as possible to prevent undue heating.

As the top of the fire pot is closed in, the main flow of air passes between the bars of the cone grate and the draft is thus carried directly through the fire to the openings in the side walls of the fire pot. The hot gases enter the chamber immediately surrounding the fire pot and flow upwardly as described, dispensing the heat against a very large radiating surface both internally 10 through the inner chamber 50 or oven and externally.

The baffle plate 32 is very important as it not only directs the gases into active contact with the exterior wall of the stove but prevents the hot gases from taking too direct a course to the smoke pipe thus insuring a uniformly heated surface throughout the exposed area of the stove.

A stove such as described may be very readily converted from a heating stove to a combination heater and cooker and in summer may be very quickly converted to use with gas, suitable gas rings 53 and 54 being placed within the fire pot and within 25 the chamber 17 and the oven thus heated very quickly.

A stove such as described has numerous advantages over the stoves now commonly in use and presenting such a large heating 30 surface it will effect a very great saving in the consumption of fuel. Further the stove presents a very ornamental appearance.

What I claim as my invention is:—

1. A stove, comprising, a base, a fire pot 25 having orifices in the side walls for the escape of the gases of combustion, means closing the top of said fire pot, a shell extending upwardly from the closed top of said fire pot and inclosing a heat chamber, and a 40 shell extending upwardly from the base and encircling the fire pot and casing extending therefrom and forming a smoke passage therearound.

2. A stove, comprising, an annular base 45 portion, a fire pot supported on said annular base portion and having openings through the side walls, a grate arranged beneath said fire pot, a casing surrounding said fire pot and supported on the base portion and extending upwardly above the top of said fire pot, an inner shell spaced from said outer casing and rising from the top of said fire pot and forming with the outer casing an annular smoke passage and inclosing 50 a heat chamber, means for closing in the top of said fire pot, a damper arranged in the top of said heat chamber, an air duct leading through said smoke passage into said heat chamber at the bottom, and means 55 for closing said air duct.

3. A stove, comprising, an annular base 60 portion, a fire pot supported on said annular base portion and having openings through the side walls, a grate arranged beneath said fire pot, a casing surrounding

said fire pot and supported from the base portion and extending upwardly above the top of said fire pot, an inner shell spaced from said outer casing and rising from the top of said fire pot and forming with the outer casing an annular smoke passage and inclosing a heat chamber, a hollow ring supported on the upper ends of said annular casings and having openings communicating with the annular smoke passage and a 70 flue at one side thereof, and an annular baffle plate arranged within said hollow ring and extending completely thereacross beneath said smoke flue.

4. A stove, comprising, a base portion, a fire pot in the form of a frustum of a cone supported on said base portion and having openings through the side wall, a grate at the bottom of said fire pot, a member inclosing the top of said fire pot, a cylindrical shell extending upwardly from said fire pot a cylindrical casing encircling said fire pot and extending upwardly and encircling said shell and forming therewith an annular smoke passage surrounding a heat chamber 80 inclosed within the inner shell, a door opening through said casing and inner shell, a door closing said opening, a cap extending over the top of the annular smoke passage having a smoke flue, and means for closing 85 the top of said chamber.

5. A stove, comprising, a base portion, a fire pot in the form of a frustum of a cone supported on said base portion and having openings through the side wall, a grate 100 beneath the bottom of said fire pot, a cylindrical shell extending upwardly from said fire pot, a cylindrical casing encircling said fire pot and extending upwardly thereabove and with said shell forming an annular 105 smoke passage around a heat chamber, a cap extending over the top of said annular smoke passage having a smoke flue therethrough, a ring extending inwardly from the top of the fire pot, a ring extending inwardly from the top of the inner shell, a cylinder extending between said rings and supported thereby within said heat chamber and forming a fuel passage through said heat chamber, and a lid adapted to close the 110 top of said cylinder.

6. In a stove, in combination, a base portion, a circular perforated fire pot supported on said base, a grate arranged beneath said fire pot, an annular casing surrounding 120 said fire pot, a perforated ring resting on said casing and fire pot, a removable top adapted to close the top of said fire pot, a pair of cylindrical shells supported on said ring and extending upwardly therefrom and inclosing an annular smoke passage, said annular smoke passage communicating with the passage between the aforesaid annular casing and said fire pot through the openings in said perforated ring, a heat chamber 125

inclosed by the inner one of said shells, a hollow ring resting on the top of said shells and forming a smoke passage and having a smoke flue therethrough, and means for closing the top of said heat chamber.

7. A stove, comprising, a base portion, a circular perforated fire pot supported from said base, a grate arranged beneath said fire pot, a ring resting on the base and encircling the lower end of the fire pot, said ring having a plurality of openings therethrough, a damper ring rotatably supported upon the aforesaid ring, an annular casing supported on said ring outside of the openings therethrough and inclosing an annular space

around said fire pot, a pair of annular shells rising from said annular casing and fire pot and inclosing an annular smoke passage, a hollow top supported on said shells and forming a smoke passage having a smoke flue therethrough, and means for closing in the top of the fire pot.

Signed at the city of Toronto, county of York, Ontario, Canada, this 10th day of May, 1911.

GRANT SMITH.
